(57) **CLAIM**

The ornamental design for a plasma treatment device for implant surface, as shown and described.

DESCRIPTION

FIG. 1 is a perspective view of a plasma treatment device for implant surface showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

The features of the plasma treatment device for implant surface shown in broken lines form no part of the claimed design.
